(57) **CLAIM**

The ornamental design for a boot cup light, as shown and described.

DESCRIPTION

FIG. 1 is a perspective view of the boot cup light showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded view showing the cup stand separated; and,

FIG. 10 is a cutaway view of a portion indicated with numeric 10 in FIG. 1.

The broken lines shown in the drawings represent portions of the boot cup light that form no part of the claimed design.

1 Claim, 10 Drawing Sheets
